J. L. CREVELING,
REVERSIBLE BRUSH HOLDER FOR DYNAMOS,
APPLICATION FILED SEPT. 25, 1911.

1,164,260.

Patented Dec. 14, 1915.

UNITED STATES PATENT OFFICE.

JOHN L. CREVELING, OF NEW YORK, N. Y., ASSIGNOR TO SAFETY CAR HEATING AND LIGHTING COMPANY, A CORPORATION OF NEW JERSEY.

REVERSIBLE BRUSH-HOLDER FOR DYNAMOS.

1,164,260.

Specification of Letters Patent. Patented Dec. 14, 1915.

Application filed September 25, 1911. Serial No. 651,022.

To all whom it may concern:

Be it known that I, JOHN L. CREVELING, a resident of New York, in the county and State of New York, have invented certain new and useful Improvements in Reversible Brush-Holders for Dynamos, as set forth in the annexed specification and drawing, forming a part thereof.

My invention pertains to that class of 10 dynamos in which the armature is subject to reversals in direction of rotation and has for its particular object to provide means whereby the current delivered by the dynamo to line will remain uni-directional 16 regardless of such reversals.

Figure I is a partial longitudinal section and elevation of a portion of the dynamo comprehending my invention. Fig. II is a transverse section of the dynamo 20 shown in Fig. I on the line A—B as viewed from the right. Fig. III is a plan of one of the brush carrying members shown in Figs. I and II.

In the drawing, 1 represents the armature 25 of the generator provided with the usual commutator 2 and carried by the shaft 3, one end of which is supported in the usual bearing carried within the bearing member 4 provided with the flanged portion 5 30 attached, as by screws 6, to the shell or field frame 7. The member 4 carries the annular magnet frame 8 which may be formed integral therewith if desired and provided with a winding 9 so as to form an 35 annular electromagnet having in operative relation thereto armatures, or shoes, 10 of magnetic material provided with arms 11 attached to and insulated from brush carrying members 12 adapted to carry brushes 13 and 40 provided on each side with members 14 adapted to carry scrubbers 15 which are made of insulating material and adapted to rest upon the commutator. The scrubbers 15 are held in place within members 14 45 as by screws 16. As a four pole machine is chosen for illustration, the brush carrying members as shown in Fig. II are four in number and may be joined together by the springs 17 so as to rest upon and 50 round the commutator 2 as shown in Fig. II. The member 4 is provided with a hub 18 which carries flanges 19 in such manner as to form a recess within which are placed rollers 20 attached to the arms 11 and thus 55 these rollers and flanges will hold the brush

carrying members from lateral play. The brush carrying members are each provided with an angular conducting member 21 attached thereto to which may be connected the leads 22 and, as the entire brush carrying mechanism will tend to revolve with the commutator and as it is desirable to arrest this revolution so as to hold the brushes in certain fixed positions, I utilize the leads 22 for this purpose. Therefore, the leads 60 22 are flexible and are attached to additional conducting members 23 insulated from the frame 7 as indicated in Fig. II, and as the brushes of a four pole machine will be shifted from one axis of commutation to that of opposed polarity by revolution of 90 degrees, I so position the members 23 and arrange the length of the leads 22 that when the brush carrying mechanism is restrained from revolution in one 70 direction, the brushes will be in their proper positions upon the axis of commutation, and if the armature revolves in a reverse direction the brush carrying mechanism will 75 revolve therewith until restrained by the 80 leads 22, 90 degrees from the position previously occupied. Hence, the direction of current delivered to line will remain constant regardless of the direction of rotation of the armature in an obvious manner. 85

The operation of my invention is substantially as follows: If the armature revolve slowly in such direction that its uppermost part in Fig. I is moving toward the observer, or is moving in a counter-clockwise 90 direction, viewing Fig. II, the brushes will be in the positions shown in Fig. II and the scrubbers 15 will be drawn upon the commutator in such manner as to clean and polish the same. If the generator 95 speed be increased until its voltage is appreciable, or that sufficient to be useful, the winding 9 which is preferably placed in shunt across the brushes will be energized and caused to attract the shoes 10 100 and lift the scrubbers 15 free from the commutator. The brushes 13, however, will remain upon the commutator in operative relation thereto owing to the action of the spring brush holders shown in the drawing. 105 If now the armature continue to revolve, the brush mechanism will all be held firmly in place by the magnet 8—9 which will firmly grip and hold the shoes 10, thus avoiding undue strain on the leads 22. If now the 110

armature become stationary, the shoes 10 will be released and the brush mechanism will assume the position shown in Figs. I and II. If the armature now be revolved 5 in a reverse direction, the brushes will revolve with the commutator through 90 degrees and then be arrested by the leads 22. If then the speed increase sufficiently the magnet 8-9 will again attract the shoes 10 and lift the scrubbers free from the armature and hold the brush rigging firmly in proper position and the current delivered to line will remain of the same polarity owing to the new position occupied by the brushes. 15 It will be observed that the arc through which the brushes are shifted when the dynamo reverses is determined by the lengths of the conductors 22, these conductors stopping the movement of the brushes in either 20 direction.

I make no claim herein to a plurality of brushes rotatably held upon the commutator and adapted to be held from rotation at predetermined points by magnetic means, since 25 such subject-matter is covered in claims of my co-pending application filed the 7th day of August, 1911, Serial No. 642,582; nor do I claim herein brush-holders in operative 30 relation to the commutator, together with electromagnetic means for supporting said brush-holders out of contact with any of the moving parts of the machine, since said subject-matter is covered by claims in my patent granted April 15, 1913, No. 1,058,730. 35 I do not wish in any way to limit myself to the exact construction shown in the drawing which is given merely to illustrate one type of dynamo comprehending my invention, for it is obvious that wide departure 40 may be made in the way of construction without departing from the spirit and scope of my invention which is as set forth in the following claims:

1. Means for commutating the current of 45 a dynamo electric machine embracing a commutator, a plurality of brush carrying members mechanically connected together and holding commutating brushes, means for securing the brushes, when in proper 50 place, from chattering, and a plurality of arms connecting said means to the brush carrying members.

2. Means for commutating the current of 55 a dynamo electric machine embracing a commutator, a plurality of brush carrying members mechanically connected together and holding commutating brushes, a plurality of insulating devices connected with said brush carrying members and bearing 60 frictionally upon the commutator; together with means for restraining the movement of the brushes in opposite directions.

3. Means for commutating the current of 65 a dynamo electric machine embracing a commutator, a plurality of brush carrying mem-

bers mechanically connected together and holding commutating brushes, means for securing the brushes, when in proper place, from chattering, and a plurality of arms connecting said means to the brush carrying 70 members; together with means for restraining the movement of the brushes in opposite directions.

4. In a generator provided with an armature and commutator, the combination of 75 brushes in operative relation to said commutator, means carried by said commutator for mounting said brushes subject to movement with said commutator, and means for restraining the movement of said brushes, said 80 brush-mounting means comprising means resting on the commutator for supporting said brush-mounting means.

5. In a generator provided with an armature and commutator, the combination of 85 brushes in operative relation to said commutator, means carried by said commutator for supporting said brushes and allowing movement with said commutator, means for restraining said movement and electromag- 90 netic means for supporting said brush carrying means.

6. The combination with a commutator, of brush carrying mechanism supported by 95 said commutator and electromagnetic means for relieving the commutator of said brush carrying mechanism and supporting the same.

7. The combination with a commutator, of brush carrying mechanism carried thereby and tending to revolve therewith, means for restraining the revolution thereof at predetermined points allowing the brushes to travel with the commutator to proper ends of axis of commutation to hold the current 100 direction uniform throughout reversals in direction of the commutator and electromagnetic means for relieving the commutator of the brush carrying mechanism and holding the same in fixed positions. 110

8. The combination with a generator provided with a commutator; of a plurality of brushes in operative relation to the commutator; means for securing said brushes together so that they may move as a unit 115 relatively to the commutator, and flexible means for arresting the movement of said brushes at a predetermined point in their movement.

9. The combination with a generator provided with a commutator, of a plurality of brushes arranged in operative relation to said commutator; means for securing said brushes together so that they may move as a unit relatively to the commutator; flexible 120 means for limiting the movement of the brushes; and additional means for restraining the movement of said brushes so as to avoid undue strain upon the flexible means. 125

10. The combination with a generator pro- 130

- vided with a commutator, of a plurality of brushes arranged in operative relation to said commutator; means for securing said brushes together so that they may move as a unit relatively to the commutator; flexible means for limiting the movement of the brushes; and magnetic means for holding the brushes from movement to thereby relieve the flexible means from undue strain.
11. The combination with a generator provided with a commutator, of a plurality of brush-holders arranged in operative relation to the commutator, said brush-holders carrying scrapers and brushes in coöperative relation to the commutator.
12. The combination with a generator provided with a commutator, of a plurality of brush-holders arranged in operative relation to the commutator, said brush-holders carrying brushes and scrapers in coöperative relation to the commutator; and means for lifting the scrapers from operative position during predetermined periods in the operation of the commutator.
13. The combination with a generator provided with a commutator, of brush-holders in operative relation to the commutator, each of said brush-holders carrying a fixed scraper and a movable brush in coöperative relation to the commutator; and means for lifting the scrapers out of operative position during predetermined periods in the operation of the commutator.
14. The combination with a generator pro-
- vided with a commutator, of a plurality of brush-holders arranged circumferentially of the commutator and in operative relation thereto; means for yieldingly joining the brush-holders together so that they may move as a unit relatively to the commutator; brushes and scrapers carried by the brush-holders; means for limiting the movement of the brush-holders relatively to the commutator; and means for moving the scrapers from coöperative relation to the commutator, at predetermined periods during the operation of the latter.
15. In combination with a generator provided with a commutator, of a brush-holder arranged in coöperative relation to the commutator, said brush-holder having a brush yieldingly pressed into engagement with the commutator, and a scraper fixedly held for engagement with the commutator.
16. In combination with a generator provided with a commutator, of a brush-holder arranged in coöperative relation to the commutator, said brush-holder having a brush yieldingly pressed into engagement with the commutator, a scraper fixedly held for engagement with the commutator, and means for lifting the scraper from engagement with the commutator without disturbing the relation of the brush thereto.

JOHN L. CREVELING.
